CLAIM

The ornamental design of a vacuum cleaner nozzle, as shown and described.

DESCRIPTION

FIG. 1 is a perspective view of a vacuum cleaner nozzle showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a rear elevational view thereof; and,

FIG. 7 is a bottom plan view thereof.

The portion of the vacuum cleaner nozzle shown in broken lines is for illustrative purposes only and forms no part of the claimed design.
